UNITED STATES PATENT OFFICE.

GUY MARDOCK, OF ILLINOIS CITY, ILLINOIS.

INSULATOR-SUPPORT.

1,127,474.

Specification of Letters Patent.

Patented Feb. 9, 1915.

Application filed February 16, 1914. Serial No. 819,049.

To all whom it may concern:

Be it known that I, GUY MARDOCK, a citizen of the United States, residing at Illinois City, in the county of Rock Island and State 5 of Illinois, have invented certain new and useful Improvements in Insulator-Supports, of which the following is a specification, reference being had to the accompanying drawings.

10 This invention comprehends certain new and useful improvements in cross arms for telephone and telegraph poles and has for its primary object to provide a device of this character which will be strong and durable, 15 as well as highly efficient in use.

Another object is to provide a device of this character in which the insulator is securely fastened upon the bracket secured to the cross arm, thereby eliminating all 20 danger of the insulator working off of the bracket.

A further object is to generally improve and simplify the construction of devices of this character and increase the efficiency 25 thereof, without increasing the cost of the same.

With the above and other objects in view, my invention consists in certain novel constructions, combinations, and arrangements 30 of parts to be hereinafter more fully described, claimed, and illustrated in the accompanying drawings, in which,

Figure 1 is an elevational view of my complete device in use; Fig. 2 is a transverse 35 sectional view thereof; and Fig. 3 is a detail elevational view showing only a portion of the cross arm.

Referring more specifically to the drawings in which similar reference characters 40 designate corresponding parts throughout the several views, 1 designates the cross arm which is formed of angle iron and adapted to be secured to a telephone or telegraph pole by bolts 2 or other suitable means, one angle 45 of the arm being positioned against the post while the remaining angle projects laterally from the same. Upon the last mentioned angle of the cross arm are positioned the upstanding insulator supports 3 upon the 50 upper ends of which are threaded or other-

wise engaged, the insulators 4 formed of any suitable non-conducting material such as glass. The upstanding insulator supports 3 are secured in position upon the upper face of the laterally directed cross arm 1 by the 55 bolts 5 extended longitudinally therethrough and through the angle of the cross arm upon which the insulator supports are positioned, said bolts also extending through the insulators 4 and having their slotted heads 6 engaged upon the upper ends of said insulators. The bolts 5 therefore, serve to securely fasten the insulators in position upon the insulator supports 3, as well as securing the latter upon the cross arm, it being understood that a nut 7 or the like is secured upon the lower end of each bolt 5.

It will be apparent that the cross arm 1, insulator supports 3, and bolts 5, are formed of any suitable material, while the insulators 4 are formed of glass or other suitable and durable non-conducting material, thereby providing a complete device which will be strong and durable as well as highly efficient 75 in use and cheap and easy to manufacture and assemble. If desired, a brace bar 8 may be employed as a further support for the cross arm, one end of the brace bar being secured to the cross arm near one end thereof, the opposite end of the bar 8 being secured to the pole below the cross bar.

While I have shown the preferred embodiment of my invention, it will be understood that minor changes in the details of construction and arrangement of parts may be made within the scope of the appended 80 claim without departing from the spirit of my invention or sacrificing any of the advantages of the same.

What is claimed is:—

A device of the class described comprising a base, an insulator support having a tapered upper end mounted upon the base, an insulator having a tapered recess formed in its lower end fitting snugly upon and being 95 engaged over said support, said support and insulator having central longitudinal registering openings therethrough, a bolt adapted for engagement through said registering 100 openings and through the base to secure the

insulator to the support and the insulator and support to the base whereby to draw the insulator down into firm engagement with the tapered support, and said insulator having a groove formed in its periphery to receive a conducting wire.

In testimony whereof I hereunto affix my signature in the presence of two witnesses.

GUY MARDOCK.
